UNITED STATES PATENT OFFICE.

ROSS F. MAHER, OF ST. PAUL, MINNESOTA, ASSIGNOR OF ONE-HALF TO GEORGE W. KOEHLER, OF RAMSEY COUNTY, MINNESOTA, AND ONE-HALF TO HENRY HINRICH, OF MANITOWOC COUNTY, WISCONSIN.

DESIGN FOR A BILLIARD-TABLE.

43,541.

Specification for Design.

Patented Feb. 11, 1913.

Application filed October 28, 1912. Serial No. 728,285. Term of patent 7 years.

To all whom it may concern:

Be it known that I, Ross F. MAHER, a citizen of the United States, residing in the city of St. Paul, county of Ramsey, and State of Minnesota, have invented a new, original, and ornamental Design for Billiard-Tables, of which the following is a specification, reference being had to the accompanying drawing, forming part thereof.

The figure is a perspective view of a billiard table, showing my new design.

I claim:

The ornamental design for a billiard table, as shown.

ROSS F. MAHER.
